UNITED STATES PATENT OFFICE.

HENRY ROY SPANGLER, OF PUEBLO, COLORADO.

ENGINE-TESTING DEVICE.

Application filed April 15, 1921. Serial No. 461,618.

To all whom it may concern:

Be it known that I, HENRY R. SPANGLER, a citizen of the United States, residing at Pueblo, in the county of Pueblo and State of Colorado, have invented certain new and useful Improvements in Engine-Testing Devices; and I do declare the following to be a full, clear, and exact description of the invention, such as will enable others skilled in the art to which it appertains to make and use the same.

This invention relates to an improved device especially designed for use by one man for the purpose of accurately testing and locating various troubles in multiple cylinder internal combustion engines, the same being permitted to be used without removing or displacing any of the wires or electrical connections.

20 The invention aims to provide a device of this class which will enable a repairman to accurately locate foul spark plugs, ascertain whether or not the compression in the cylinder is adequate, to detect engine 25 "knocks", and to locate various other defects and faults whether they occur in the carburetor, distributor, breaker box or various other parts of the engine.

30 The invention also aims to devise a device of this class which is an improvement over prior patented and marketed devices used for accomplishing similar ends, this improved device being simple, convenient to manipulate, very effective in operation, and 35 inexpensive to both the manufacturer and the user.

Other objects and advantages of the invention will be apparent during the course of the following description.

40 In the accompanying drawings forming a part of this specification and in which like numerals are employed to designate like parts throughout the same:

Figure 1 is a top plan view of a device 45 constructed in accordance with this invention, showing the same connected to spark plugs of an internal combustion engine.

Figure 2 is a central transverse section taken substantially on the plane of the line 50 2-2 of Fig. 1.

Figure 3 is a detail view of one of the clips designed for engagement with the spark plug terminals.

55 Referring to the drawing by numerals, 1 designates a base which of insulation material which in its preferred form is nar-

rowed at its inner end, the outer edge thereof being curved as shown. Secured by screws 2 or other suitable fastenings to the upper face of the base and abutting the rib 1^a at the narrow end of the base is a plurality of rectangular strips of insulating material 3 which are of less length than the base and have their outer ends terminating short of the adjacent edge of the latter. Secured to the inner ends of the insulating strips 3 and extending beyond them, is a conductor plate 4 which, by preference, is secured in place by the same screws which serve to connect the insulating strips to the base as already described. It is to be noted that the inner fastenings pass through the plates 5^a, conductor, inner ends of the insulating strips 3, and into the insulated base 1. Hence, a single fastening serves to secure several parts together. Arranged near the outer ends of the insulating strips are a plurality of small plates 5 which carry integral or separate spaced upstanding contact fingers 6 which constitute a part of the switches to be hereinafter described. It may be pointed out here, that these plates 5 are, like the plates 4, secured to the insulating strips and base by means of the same screws which serve to secure the insulating members to the base. Similar plates 5^a including upstanding spaced fingers 6^a are secured to the plate 4 directly opposite the plates 5. It may be noted however that the plates 5^a are rather closely spaced from one another while the similar ones at the outer ends of the insulating strips are spaced greater distances from one another. The plates 5 and 5^a together with the metallic 95 blades 7 which are pivoted between the fingers 6^a constitute switches of the single throw type. As is usual, the blades 8 are equipped with fibre handles 8 for operating them. With this arrangement, it will be seen that the switches are spaced from one another and are arranged in divergent relation. Secured to the plates 5 in any way, such for instance as by means of the adjacent screws 2, are a plurality of wires 9 which, when in use lead to the various spark plugs S on the cylinder head H. For convenience of connection of these wires with the spark plugs, the wires are equipped on their free ends with spring clips 10 of the type more clearly disclosed in Fig. 3. With this construction, it will be

seen that the wires can be easily and quickly connected and disconnected to or from the spark plugs as the case may be. The device in addition to the foregoing parts, 5 embodies a handle 11 which is detachably or otherwise secured to the base 1, serving as it will be seen, to conveniently handle and manipulate the device.

It is to be noted that the device as shown 10 embodies seven switches, although it could embody more or less as desired. The particular type of device shown is designed, as is obvious, for use in connection with six cylinder engines, there being a sufficient 15 number of wires 9 for permitting this. The additional switch at the extreme right hand end of the device may be well designated by the numeral 12, the same being here conveniently termed as the "ground" switch, 20 and the wire 12^a leading from it being designed for connection with the cylinder head or other metallic part of the automobile to create a ground and short-circuit the current supplied to any one of the spark plugs. 25 The blade of this switch is therefore usually closed as indicated.

In use, the various clips 10 are detachably connected with the thumb screws or electrodes of the spark plugs S in the manner 30 shown in Fig. 1, the device itself being held by the handle 11 or placed on any suitable support as desired. Now, when it is desired to test the various spark plugs, the switches are selectively and successively 35 closed, causing the current to the spark plugs to be short circuited and grounded, it being obvious that if a particular switch is closed, the current will pass through the wire leading thereto, through the switch, 40 through the conductor or distributor plate 4 and thence through the switch 12 and ground wire 12^a leading therefrom to the part of the engine to which it is connected. If irregular engine action is due to poor 45 ignition and the trouble seems to be localized in any particular part of the engine or circuit, it can be very easily and readily located by operating the various switches and short circuiting the desired spark plugs. It may

be found that all but one of the cylinders 50 are functioning properly and only one is at fault. In this case, it indicates that the trouble is present either at the spark plug or from some condition of the cylinder other than faulty ignition. With only the one 55 cylinder operating it will be an easy matter to ascertain whether the compression is normal or weak, as any hissing noise can, with a single cylinder running, be easily detected. As the remaining cylinders are only temporarily 60 out of action, they can be easily and quickly rendered operative by opening the switches selectively.

From the foregoing description, it will be seen by use of my improved device that 65 a repairman will not only be enabled to locate foul spark plugs, but will be enabled to effect a test of the compression in the cylinder, locate faulty adjustment of the carburetor, engine "knocks" and various 70 other conditions which tend to render the operation of the engine as a whole, faulty. These and other advantages of the invention have, no doubt, become apparent from the foregoing description and drawings. 75 Therefore, a more lengthy and detailed description is thought unnecessary.

Slight minor changes coming within the scope of the subjoined claim may be 80 resorted to.

I claim:

A spark plug testing device comprising a base having a rib on its upper face extending longitudinally along one edge and providing a shoulder, a plurality of strips of insulation material arranged in spaced relation and having their inner ends abutting said shoulder, a conductor resting on the upper faces of said insulating strips and extending over and resting on the upper face of said rib, circuit closures including contacts resting on said insulating strips and conductor respectively, and fastenings 85 passing through said contacts, conductor, insulating strips and into said base. 90

In testimony whereof I have hereunto set my hand.

HENRY ROY SPANGLER.
